UNITED STATES PATENT OFFICE

WILSON A. SMITH, OF ELKHART, INDIANA, ASSIGNOR TO THE ADLAKE COMPANY, OF CHICAGO, ILLINOIS, A CORPORATION OF ILLINOIS

DESIGN FOR A SASH LATCH

Application filed July 16, 1930. Serial No. 36,365. Term of patent 7 years.

To all whom it may concern:

Be it known that I, WILSON A. SMITH, a citizen of the United States, residing at Elkhart, in the county of Elkhart and State of Indiana, have invented a new, original, and ornamental Design for a Sash Latch, of which the following is a specification, reference being had to the accompanying drawings, forming a part hereof.

The sash latch of my invention is a complete integral article of manufacture.

In the illustration,

Fig. 1 is a perspective view of a sash latch, showing my new design; and

Fig. 2 is another perspective view of the same latch.

What I claim is:

The ornamental design for a sash latch, substantially as shown and described.

WILSON A. SMITH.
